D. BROMLEY

Attorney

UNITED STATES PATENT OFFICE.

DANIEL BROMLEY, OF CARROLLTON, KENTUCKY.

DOOR-SECURER.

SPECIFICATION forming part of Letters Patent No. 334,636, dated January 19, 1886.

Application filed October 29, 1885. Serial No. 181,332. (No model.)

To all whom it may concern:

Be it known that I, DANIEL BROMLEY, a citizen of the United States of America, residing at Carrollton, in the county of Carroll and State of Kentucky, have invented certain new and useful Improvements in Door-Securers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in portable door-securers, the object being to provide a fastening device for doors with a combination-lock attached thereto, so as to provide a fastening device 20 which will prevent the door from being opened from the outside as well as from the inside, where the fastening is located, except by a person familiar with the combination.

My invention consists in a door-securer 25 which is provided with disks having indicating marks on their peripheries, said disks being provided on their inner sides with openings with notches for the reception of open rings, which must be placed so as to register 30 with each other before the parts of the fastener can be moved, so as to allow the door to be opened.

My invention also consists in the construction and combination of parts, as will be hereinafter fully set forth, and specifically pointed out in the claims.

In the accompanying drawings, which illustrate my invention, Figure 1 is a side view of my improvement, showing the same closed, or 40 in a position to be carried in the pocket. Figs. 2 and 3 are longitudinal sectional views. Fig. 4 is a vertical sectional view taken through the line xx of Fig. 2. Fig. 5 is a similar view taken through the line yy . Fig. 6 is a detail 45 perspective view of one of the disks of the combination-lock. Fig. 7 is a detail perspective view of an open ring which is adapted to fit within the disk shown in Fig. 6. Fig. 8 is a perspective view of the hasp detached from 50 the lock. Fig. 9 is a front view of the lock, and Fig. 10 is a view of the operating-disk

which engages with the screw-threads of the hasp.

A represents the body portion of my improved door-fastener, which consists of an end piece, a , one or more of the sides of which are cut away, as shown at a' , and adjacent to this end piece is a circumferential recess, a'' , within which lies a collar, B, which has a projecting flange, b , one side of said collar and flange 60 being cut away, as shown at b' , so as to be on a line with a cut-away portion, a' , of the end piece, a . Adjacent to the circumferential recess a'' is an enlarged portion, A' , which is formed on or attached rigidly to the body portion A , and said portion A' may have one or more of its sides cut away, so as to provide straight edges, which will be in the same plane longitudinally as the straight end piece, a . A circumferential recess, a''' , for the reception of 70 the ring C of the disk, is formed in the body portion A adjacent to the part A'' , and the part a''' is cut away on one or opposite sides, so that its interior screw-threaded portion will engage with the threads of the hasp, and 75 from the outer side of this portion A''' extends the cylindrical end a''' , one side of which is provided with a longitudinal recess, d , which extends from its end to the front end of the portion A'' , thus providing a passage-way in 80 which the pin e , which is attached to the side of the hasp E , may play.

It will be noted in the construction hereinbefore described that the parts a , A' , A'' , A''' , and A'''' are all formed from a single piece of 85 metal and are integral with each other, the recesses a'' , a''' , and d being formed therein.

The hasp E , as shown in Fig. 8, is made of a flat piece of metal having screw-threaded sides, and from one of said screw-threaded 90 sides projects a pin, e , which is adapted to fit within the recess d , the outer end of said hasp having the end portion which is bent at right angles, and is adapted to enter the door-frame and to be pressed into said frame when the 95 door is closed thereon. The opening through which the shank of the hasp passes is oblong or rectangular in cross-section, and the slot d , hereinbefore referred to, is formed by increasing the depth at its long sides, so as to provide 100 a space through which the pin e may pass, this cut extending entirely through the end portion

A'' , and continuing an equal depth until it reaches the connecting portion a''' between the parts A' and A'' .

Upon the end portion A'' are placed combination-rings F , the opening f therein being of a sufficient depth to allow the pin e to pass through the same, and these open rings are provided opposite the openings f with projecting portions f' , which enter recesses g in the rings or disks G , said disks being provided on their peripheries with indicating-marks—as figures or letters. It will be evident that by placing the projecting portion f' in different recesses of the disks G the combination can be changed. When the projection f' is placed in one of the recesses g of the disk G , an opposite recess will register with the opening f , which is of sufficient depth to allow the pin e to pass through the same.

20 The disks of the combination-lock are held in place by an end piece, H , which is screw-threaded on its interior, so as to engage with the threads on the tubular end of the body portion A , and this end piece may be held thereon by a set-screw, h , which will prevent the same being unscrewed. A ring is passed through an eye in the end piece H , and forms a convenient means for attaching the door-fastener to a key-ring or other object.

25 30 The disk C , as shown in Fig. 10, is made up of two parts, which are notched, and said parts are connected to each other by rivets. The notches within which the heads of the rivets lie are afterward filled with metal, so that 35 the joint will be imperceptible. The flange-ring B is also made in two parts, which may be held together in a similar manner, or its periphery may have the flange portion B brazed thereon. The periphery of the disk C is milled, 40 so that it can be readily turned, and by turning the same the shank of the hasp can be thrown into the body portion or extended therefrom.

To attach my improved fastener to a door 45 so as to hold the same in a closed position, the combination is first set so that the openings f in the rings F will be on a line with each other, and also on a line with the pin e , which projects from the hasp. The disk C is then turned 50 so that it will force the hasp out of the body portion, said pin being located near the disk C . The ring B is then turned so that its straight portion a will be on a line with the straight side a' of the end piece a . The hasp 55 is then inserted in the door-jamb and the door

closed thereon. The straight sides of the end piece and ring B allow the door to close upon the hasp. After the door is closed the ring B is turned partially around, and the body portion, by turning the disk C , is brought against 60 the edge of the door-jamb. The disks of the combination-lock are then turned so as to prevent the pin sliding beyond the same, thus securing the hasp so that it cannot be moved within the case without first setting the lock 65 at the proper combination.

By means of my improved device a door can be locked from the inside of a room, so that it cannot be opened without first removing the fastening device, and said fastening 70 device cannot be removed except by a person familiar with the combination. Thus if a person is sharing a compartment with a stranger he can lock the door, so as to be free from intrusion without, and the person sharing the 75 room cannot leave the same without his knowledge or being made familiar with the combination.

I claim—

1. In a door-securer, the combination, with 80 a case, A , of a hasp, E , having a portion playing in said case, and provided at its free end with an angular portion adapted to be inserted and retained between the door edge and jamb, and a combination-lock for locking said 85 hasp, substantially as set forth.

2. In a door-fastening device, the combination, with a movable hasp with angular projecting portion and body portion A , recessed for the reception of said shank, and having an 90 end, a , with a straight side, of a movable ring attached to said end portion and provided with a cut away side, substantially as shown, and for the purpose set forth.

3. In a door-fastener, the combination, with 95 a body portion constructed substantially as shown, and provided with a longitudinal recess for the reception of a flat screw-threaded shank, of a hasp and operating-ring, C , secured upon the body portion and adapted to 100 engage with a hasp, the disks G , and opened rings F , attached to the body portion, the parts being combined and organized substantially as shown, and for the purpose set forth.

In testimony whereof I affix my signature in 105 presence of two witnesses.

DANIEL BROMLEY.
